CLAIM

The ornamental design for a bar stool as shown and described.

DESCRIPTION

FIG. 1 is a perspective view of a bar stool showing my new design;

FIG. 2 is a front view thereof;

FIG. 3 is a rear view thereof;

FIG. 4 is a right side view thereof;

FIG. 5 is a left side view thereof;

FIG. 6 is a bottom view thereof; and,

FIG. 7 is a top view thereof.

Broken lines in the drawings depict portions of the bar stool that form no part of the claimed design.
